RAILROAD FROG STRUCTURE

John G. Budin, Chicago, Ill.

Application June 13, 1952, Serial No. 293,363

7 Claims. (Cl. 246—463)

The present invention relates to improvements in railroad frog structures such as are used in railway tracks, and the invention is adaptable to turnout frogs or crossing frogs.

The frog structures at rail crossings and changeovers are subjected to especially hard usage by reason of the necessity for the locomotive and car wheels traveling thereover to move across the gap provided at the frog point for clearance of the wheel flanges. This results in severe pounding and shocks and vibrations with virtually hammering effects as the wheels travel over the crossing.

The point of the frog is, of course, especially vulnerable. Conventionally, the point of the frog is provided by the pointed portion of one of the two rails that converge at the heel of the frog toward the point, and referred to as the long point rail with which converges rearwardly from the point a short point rail.

In the conventional construction, the convergence requires severe bending of the long and short point rails rearwardly from their tips to provide the proper frog angle, resulting in straining and weakening the rails at the bends therein and constituting a major fracture hazard at the bends.

It has been proposed to provide special castings to afford the point section of the frog. However, such castings are expensive to produce and are liable to fractures.

It is an important object of the present invention to provide an improved railway frog construction in which the point portion of the frog is constructed of standard rail free from bends and related to the other elements of the frog in strongly reinforcing, stabilizing cooperation.

Another object of the invention is to provide an improved railway frog construction in which bending of the rail sections at the heel of the frog is greatly minimized.

A further object of the invention is to provide an improved railway frog construction having a novel long point rail member.

Still another object of the invention is to provide a simplified and strengthened railway frog construction.

Yet another object of the invention is to effect substantial economies in railway frog constructions.

Other objects, features and advantages of the present invention will be readily apparent from the following detailed description of certain preferred embodiments thereof taken in conjunction with the accompanying drawings in which:

Figure 1 is a top plan view of a railway frog construction embodying the features of the present invention and in certain respects illustrated more or less schematically;

Figure 2 is a more or less schematic bottom plan view of the frog construction of the present invention;

Figure 3 is a side elevational view of the long point rail element of the improved frog construction;

Figure 4 is an enlarged transverse sectional view taken substantially on the line IV—IV of Figure 1;

Figure 5 is an enlarged transverse sectional view taken substantially on the line V—V of Figure 1;

2

Figure 6 is an enlarged transverse sectional view taken substantially on the line VI—VI of Figure 1;

Figure 7 is an enlarged fragmentary top plan view of that section of the frog where the short point rails join the long point rails;

Figure 8 is a fragmentary side elevational view of the tip portions of one of the short point rails; and

Figure 9 is a fragmentary top plan view of the heel portion of a slightly modified form of the invention.

10 As shown on the drawings:

A rail frog construction embodying the present invention, and as illustrated in Figures 1 and 2, comprises symmetrically arranged and cooperatively related heel and toe portions wherein the heel portion includes complementary short point rails 10 and 11 convergingly related and secured to respectively opposite sides of a long point intermediate rail section 12 disposed on the center line of the frog. The toe portion of the frog includes a pair of complementary, symmetrically arranged wing rail members 13 and 14. All of the rail elements or units are secured rigidly together in the frog by means of appropriately placed transversely extending bolts 15, schematically indicated in Figure 1 and fully shown in Figures 4, 5 and 6.

20 According to the present invention, the long point rail member 12 provides an efficient, stable load-supporting member of great ruggedness. To this end, the long point rail member 12 comprises an elongated piece of rail of standard section conformable to the weight of rails used in the track and thus requiring no special section, but meeting all of the standards of the rail with which associated since it is actually a piece of the same standard rail specified for the particular trackage with which the frog is to be used. As best seen in Figures 1, 2 and 3, the long point rail member 12 is perfectly straight. Throughout the major portion of its length, the long point member 12 has the head and the base flange thereof of full width, while the web remains substantially unaltered throughout the length of the piece except, of course, for appropriate spaced transverse bolt holes 17. At its heel end, the head of the long point rail is slightly chamfered on top as indicated at 18 for wheel clearance. At its point end, the long point rail is appropriately tapered at its sides symmetrically to the frog angle, as indicated at 19, including both the head and the base flange of the rail. Moreover, the point portion of the head of the long point rail is tapered forwardly as indicated at 20 for wheel clearance while the upper portion of the extreme end of the web is recessed or cut away as indicated at 21 for wheel flange clearance.

30 Each of the short point rail members 10 and 11 has the side of the forward end portion of its head planed to a tapering angle complementary to the longitudinally straight sides of the head of the point rail member 12 for close abutment against the sides of the long point rail member head, as best seen in Figures 1 and 7, at 22. At approximately the heel ends of the tapers 22 of the short point rail members, they are bent slightly as indicated at 23 on an angle to preferably half the frog angle so that the webs of the short point rails will converge toward and engage the respective sides of the long point rail at and extend somewhat forwardly beyond the beginning of the front end portion taper 19 of the long point rail. At their outer sides, however, the heads of the short point rails are planed to extend straight in the line with the heel portions of the short point rails, so that in the assembly the outer sides of the heads of the short point rails are straight in line with the tapers 19 of the long point rail 12.

40 50 60 70 80 90 As will be observed from Figures 5, 7 and 8, the tip end portions of the heads of the short point rails are cut away to leave forward and upper edges 24 which engage

in bracing relation under the head of the long point rail 12. In addition, the forward extremity portions of the heads of the short point rails 10 and 11 are side-chamfered as shown at 25, and top-chamfered or beveled as indicated at 27 to avoid sharp ends or edges that might catch on the car wheels. Bolt holes 28 are, of course, provided in the short point rails 10 and 11 matching with the bolt holes in the long point rail 12.

In order to accommodate and rest upon the base flange of the long point rail 12, the base flanges of the short point rails 10 and 11 are provided with clearance cutouts 29, as best seen in Figures 2 and 6. It will be observed that the width of the cutouts 29 is sufficient to afford a substantial gap at the side of the long point rail base flange for draw-up clearance. It will thus be observed that throughout the major portion of its length, the base flange of the long point rail 12 is overlapped and securely held down at both sides of the rail by the base flange portions of the short point rails 10 and 11 as provided by appropriately formed cutouts or recesses 29. This, taken together with the underlying shouldering support of the head of the long point rail 12 by the shoulders 24 at the tips of the short point rails provide an extremely stable, rigid and efficiently load-sustaining and resisting assembly, since the major load is supported by the intermediately positioned long point rail 12 disposed on the center line of the frog.

For improved solidity and rigidity in the assembly, respective elongated, properly shaped or planed filler blocks or bars 30 are secured between the adjacent sides of the short point rail and the intermediate long point rail.

Each of the wing rails 13 and 14 is intermediately bent to conform to the frog angle, as best seen in Figures 1 and 2. The toe portions of the wing rails are shorter than the remaining portions of such rails. The toe portions of the wing rails are secured in proper fixed spaced relation by means of an intermediate throat block 31 secured in place by means of bolts schematically indicated at 32.

Intermediate the angle defined between the rearward longer diverging portions of the wing rails is secured the heel assembly comprising the short point rails 10 and 11 and the long point rail 12. To maintain a proper spaced relation between the sides of the wing rails and the adjacent sides of heel portion of the frog assembly, appropriate complementary elongated spacer blocks or bars 33 are provided, and the assembly is rigidly secured together by means of the bolts 15.

As best seen in Figures 2, 4 and 5, the adjacent or inner sides of the long portions of the wing rails 13 and 14 have the base flange planed off sufficiently to afford a clearance gap 34 at each side of the forward or point portion of the long point rail base flange, and the continuations afforded by base flanges of the short point rails 10 and 11. Such gaps 34 enable secure drawing-up of the parts by means of the bolts 15. Furthermore, by trimming away inside portions of the wing rail flanges, the full effective width of the long point rail base flange is made available for stable support of the long point rail, even to a substantial extent at the point tapers 19.

At their rear end portions, the heads of the wing rails 13 and 14 are planed off at their inner sides as indicated at 35 on respective tapers to afford wheel flange safety clearance.

In the modification of Figure 9, a long heel intermediate long point rail 40 is shown in association with short point rails 41 and 42 to which are joined respective track rails 43. In effecting the joint, fish plates or joint bars 44 are applied to the outer side of the joint while respective filler blocks 45 are secured between the heel portion of the long point rail 40 and the opposing sides of the short point rails 41 and 42 and the adjacent end portions of the rails 43. In this way the end portions of the rails 43 are secured in rigid assembly with the frog through the heel portion of the intermediate long point rail 40 and the filler blocks 45. It will be understood that the point portions of the intermediate long point rail 40 and the short point rails 41 and 42 will be secured together in the same manner as described in connection with the form of Figure 1.

From the foregoing it will be apparent that the present invention provides an unusually economical railway frog construction. The intermediate long point rail is a one-piece straight stock rail placed on the center line of the frog bisecting the frog angle and is without any bends. The long point rail feature of the invention can be used for rigid bolted frogs, spring rail frogs, self-guarded frogs, bolted rail crossings and other special frogs, where conventionally bent long point and short point rails are used.

Since the intermediate long point rail is so constructed as to carry an equal load for both tracks, only one standardized frog construction will meet the requirements for either left hand or right hand frog.

By reason of the novel arrangement utilizing the intermediate long point rail of the present invention, the short point rails are substantially strengthened over conventional constructions because the length of the bend of the short point rails is doubled for half of the frog angle. Further strength in the assembly is attained because the intermediate long point rail carries most of the load in both directions of traffic.

The construction of the frog of the present invention enables uniform spacing of the bolts and equal distribution of bolt stresses throughout the frog assembly.

The present invention also eliminates the need for heel risers, cast point block and foot guards.

The intermediate long point rail member can conveniently and economically be made from standard rolled rail of the same character as the rail of the track with which the frog is to be used.

It will be understood that modifications and variations may be effected without departing from the scope of the novel concepts of the present invention.

I claim as my invention:

1. In a railway frog construction, a long point straight intermediate rail member, and short point rail members symmetrically secured to the respective opposite sides of the long point rail member and having portions of the base flanges thereof recessed complementary to and engaging upon the base flange of the intermediate long point rail member, the tip portion of the webs of the short point rail members engaging as shoulders under the head of the long point rail member adjacent to the point of the latter.

2. In combination in a railway frog construction, an elongated straight long point rail member arranged to bisect the angle of the frog, and short point rail member convergingly assembled on one side of the long point rail member, said short point rail member having a bend of as nearly as practicable half of the frog angle adjacent to juncture of the short point rail member with the heel end portion of the long point rail member, the head of the short point rail member being tapered at its inner side for substantially flush engagement with the head of the long point rail member, a portion of the base flange of the short point rail member being recessed to accommodate and lie upon the base flange of the long point rail member, the tip portion of the short point rail member shoulderingly underlying the head of the long point rail member, the point portion of the long point rail member being tapered at the sides, and the outer sides of the rail head and base flange of the short point rail member being parallel to the taper of the point portion of the long point rail, with the outer side of the head of the short point rail member in straight alignment with said taper.

3. In combination in a railway frog of all rail construction, a long point straight rail member, a pair of short point rail members convergingly related and merging with the respective opposite sides of the long point rail member, the tip portions of the short point rail members engaging the sides of the long point rail member spaced

rearwardly from the tip of the long point rail member, filler blocks disposed between the heel end portion of the long point rail member and the adjacent sides of the short point rail members, and bolts rigidly securing the long point and short point rail members and the filler blocks together.

4. A frog construction as defined in claim 3 wherein the heel end portion of the long point rail member extends substantially rearwardly beyond the ends of the short point rail members, rail members joined to the heel ends of the short point rail members, and the filler blocks serve as joint bars across the joint as well as filler blocks.

5. In combination in a railway frog of all rail construction, an intermediate straight long point rail located to bisect the frog angle, a pair of short point rail members secured to respectively opposite sides of the long point rail member and with the tip portions thereof spaced rearwardly from the tip of the long point rail member, and a pair of wing rail members lying at opposite sides of the point of the long point rail member and the points of the short point rail members, said wing rail members having the inner sides of the base flange thereof trimmed away to afford gap clearance between the edges of the wing rail base flanges and the adjacent edges of the flanges of the long point and short point rail members, and filler blocks maintaining the wing rail members in predetermined parallel spaced relation to the sides of the long point and short point rail members.

6. In combination in a railway frog of all rail construction, an intermediate straight long point rail located to bisect the frog angle, a pair of short point rail members secured to respectively opposite sides of the long

30

point rail member and with the tip portions thereof spaced rearwardly from the tip of the long point rail member, and a pair of wing rail members lying at opposite sides of the point of the long point rail member and the points of the short point rail members, said wing rail members having the inner sides of the base flange thereof trimmed away to afford gap clearance between the edges of the wing rail base flanges and the adjacent edges of the flanges of the long point and short point rail members, and filler blocks maintaining the wing rail members in predetermined parallel spaced relation to the sides of the long point and short point rail members, the heel end portions of the heads of the wing rail members being flaringly beveled for wheel flange clearance.

7. In a railway frog of all rail construction, a long point straight intermediate rail member, and short point rail members symmetrically secured to respective opposite sides of the long point rail member and having the tip portion of the webs of the short point rail members formed as engaging shoulders under the head of the long point rail member adjacent to the point of the latter.
